UNITED STATES PATENT OFFICE.

WILLIAM NANCE LEWIS, OF ABINGDON, ILLINOIS.

DESIGN FOR A BRUSH-HANDLE.

SPECIFICATION forming part of Design No. 33,821, dated January 1, 1901.

Application filed December 3, 1900. Serial No. 38,573. Term of patent 14 years.

To all whom it may concern:

Be it known that I, WILLIAM NANCE LEWIS, a citizen of the United States, residing at Abingdon, in the county of Knox and State of Illinois, have invented and produced a new and original Design for a Brush-Handle, of which the following is a specification.

This invention relates to a design for a brush-handle, and the essential feature re-
10 sides in the design illustrated in the accom-
panying drawings, wherein—

Figure 1 is a perspective view of a brush-
handle embodying the feature of the design.
Fig. 2 is a side elevation of the same.

15 The numeral 1 designates the upper mem-
ber, composed of a plurality of closely - ar-
ranged spiral convolutions 2, reducing toward

their lower termination and continuing into a loop 3, having a longitudinal concavo-convex form. The loop is also disposed at an in- 20
clination, and the said upper member is tu-
bular.

Having thus described the invention, what is claimed as new is—

The design for a brush - handle, herein 25
shown and described.

In testimony that I claim the foregoing as my own I have hereto affixed my signature in the presence of two witnesses.

WILLIAM NANCE LEWIS.
